UNITED STATES PATENT OFFICE.

CLAUDE HARRISON COOK, OF YOUNGSTOWN, OHIO, ASSIGNOR OF ONE-FOURTH TO
S. D. L. JACKSON AND ONE-FOURTH TO J. W. FAWCETT.

FUEL-VAPORIZER.

1,276,332.

Specification of Letters Patent. Patented Aug. 20, 1918.

Application filed January 7, 1918. Serial No. 210,719.

To all whom it may concern:

Be it known that I, CLAUDE HARRISON COOK, a citizen of the United States, residing at Youngstown, in the county of Mahoning and State of Ohio, have invented certain new and useful Improvements in Fuel-Vaporizers, of which the following is a specification.

This invention relates to internal combustion engines, and more particularly to an improvement in charge forming devices therefor.

To this end the invention contemplates a novel apparatus for vaporizing a heavy fuel oil or hydrocarbon such as kerosene for use in the engine. Heretofore, owing to the relatively crude and involatile character of kerosene, its more general use has been prohibited, especially in connection with carbureters of the type usually employed on automobiles 15 with gasoline as the fuel oil. In the latter case, it is well known that the gasoline becomes vaporized into an explosive gas by mixing with air taken in through the carbureter, thus causing the vaporization and 20 mixing with air to be a substantially simultaneous operation. However, on account of the relatively involatile character of kerosene as above pointed out, it is not feasible to insure practical results, to cause vaporization 25 of the kerosene simultaneously with its contact with the air.

Accordingly, the present invention has primarily in view a device by which kerosene or equivalent heavy fuel oil is first vaporized in the absence of air by the action of heat, and then this heated vaporized fuel, in an undiluted state, is conveyed to a suitable air mixer which supplies the requisite air for the mixture and the latter is then 40 taken into the intake manifold of the engine. To carry forward this object it is proposed, for the sake of convenience and economy, to utilize the heat of the exhaust of the engine as the agent for initially vaporizing 45 the kerosene; and to this end a special vaporizer unit is provided which is particularly designed to present an extended area of heating surface to the liquid fuel without assuming unwieldy proportions, and which 50 may be readily fitted in the exhaust pipe line; and conveniently connected with the source of fuel supply and air mixer associated with the intake manifold.

A further object of the invention is to 55 provide a special form of air mixer for use

in connection with the vaporizer unit above set forth, and which will thoroughly and efficiently mix the air with the heated kerosene vapor prior to its entrance into the intake manifold of the engine to provide the proper combustible charge.

With the above and other objects in view which will more readily appear as the nature of the invention is understood, the same consists in the novel construction, combination, and arrangement of parts hereinafter more fully described, illustrated and claimed.

A preferred practical embodiment of the invention is shown in the accompanying drawings in which:

Figure 1 is a more or less diagrammatic view showing the present apparatus applied to an internal combustion engine.

Fig. 2 is a side elevation of the vaporizer unit partly in section the point of section being indicated by the line 2—2 of Fig. 4.

Fig. 3 is a vertical cross section taken on the line 3—3 of Fig. 2.

Fig. 4 is an elevation of one end of the vaporizer showing the fuel intake and vapor outlet openings.

Fig. 5 is an end elevation of the end opposite that shown in Fig. 4.

Fig. 6 is a vertical cross section on the line 6—6 of Fig. 2 looking in the direction of the arrows, and more clearly illustrating (by dotted lines) the path of the vapor through the vaporizer unit.

Fig. 7 is a vertical sectional view of the air and vapor mixer.

Fig. 8 is a horizontal cross section taken on the line 8—8 of Fig. 7.

Similar reference characters designate corresponding parts throughout the several figures of the drawings.

In carrying the present invention into effect it is proposed to provide a charge forming device which primarily includes a vaporizer unit for the kerosene, wherein the latter is converted from a liquid to a vapor in the total absence of air, and is thence drawn into the special air mixer, arranged in relatively close proximity to the intake manifold of the engine, whereby the heated kerosene gas will be thoroughly mixed with the air and drawn into the engine to provide the necessary fuel charge for operating the same.

Referring now more specifically to the vaporizer unit designated generally as 1, 110

it will be observed from Fig. 1 that the same is interposed in the exhaust pipe line L of the engine E at any suitable and convenient point, and, in order to facilitate this installation the said vaporizer unit, which is preferably of cylindrical shape, is provided at each end with an internal threaded nipple extension 2. Thus, it will be apparent that when the present vaporizer device is in place it becomes, in effect, a part of the exhaust pipe line itself, whereby it receives the full benefit of all the heat of the waste gases from the engine, and as will also be observed from Fig. 1, the front end of the vaporizer has connected therewith a suitable fuel supply pipe line 3 leading from a kerosene or coal oil supply tank 4 which may be conveniently located under the seat of the automobile or elsewhere to obtain the proper gravity feed of the fuel to the vaporizer, and this same end of the vaporizer also has fitted thereto a heated kerosene-vapor conduit 5 which leads to the air mixer A connected with the intake manifold M of the engine.

Having now set forth the general features of the present charge forming system, more particular reference will be made to the novel vaporizer unit A. This unit is, as previously set forth, preferably of cylindrical shape and may be made by a casting operation or other convenient method. As shown, the said unit is particularly constructed with a view to providing a maximum heating surface over which the liquid fuel must pass in order to secure the proper vaporization, and to this end it is proposed to form the cylinder with an interior cross-shaped exhaust passage 6 which extends throughout the entire length thereof as shown in the drawings and divides the interior of the cylinder into a plurality of sector shaped compartments or chambers 7, 8, 9 and 10 which are in communication with each other, whereby the fuel must travel or pass over the greatest possible area of heating surface. That is to say, the initial liquid fuel receiving chamber 7 which receives the outlet end of the fuel supply pipe 3, has at its opposite end a suitable port 7^b which establishes communication between the chambers 7 and 8, and each of the other chambers or compartments are similarly provided as will presently appear. As shown in Fig. 3, the said port 7^b is formed transversely of one of the wings of the exhaust passage 6, so that as the fuel passes from the chamber 7 into chamber 8 it must pass through a relatively restricted orifice 60 which is directly in the line of the exhaust gases, and is of course highly heated, thus producing a maximum vaporizing effect on the fuel passing between chambers 7 and 8.

When the fuel is received by chamber 8 from the chamber 7, a small proportion

thereof may still be in liquid form, but owing to the relatively large heating surface of the chamber 8, and also the fact that in order for the gas to escape therefrom it must travel to the opposite end from which it entered, the same will be in a more highly vaporized state when it passes into the chamber 9 through the passage way 8^a in the upper wall of the chamber 8 as shown in Fig. 2, and located at the front end of the vaporizer whereas the port 7^b is located at the rear end. After entering the front end of the chamber 9 through the port 8^a, the vaporized kerosene must travel the full length of the chamber 9 in order to reach the outlet port 9^a at the rear end thereof which communicates with the chamber 10. Thus the vapor becomes superheated in chamber 9, and also in chamber 10 as it passes from the rear end of the latter toward the front end thereof which is provided with a suitable outlet nipple 10^a connecting with the vapor conduit 5 leading to the air mixer A.

From the foregoing it will be apparent that the liquid kerosene from the fuel tank 4 will be fed by the pipe 3 into the front end of the chamber 7 where it becomes heated and partially vaporized and then the liquid and vapor will make their way in the manner above described into the chamber 8; where all of the liquid becomes vaporized and then the vapor only passes on through chambers 9 and 10, while being exposed to a high degree of heat, in the total absence of air. Thus, the vapor discharged from the chamber 10 through the outlet 10^a into the pipe 5 is pure undiluted kerosene vapor in a highly heated state, and this vapor is conveyed in this condition to a point in relatively close proximity to the engine where it is mixed with suitable proportions of air to form the explosive charge for the gas engine. That is to say, this highly heated kerosene vapor is conveyed through the pipe 5 directly to the inlet connection 11 of the air mixer A which is preferably of the special construction shown in Fig. 7 of the drawings.

As will be observed from the said figure this air mixer embodies in its organization a suitable conical casing 12 having a constricted outlet 13 and provided with a suitable flange 14 for connecting with the intake manifold M, and another flange 15 for facilitating the connection of the flange 16 of the valved gas supply base 17 therewith. This latter member which includes the intake connection 11 is formed with an annular gas supply chamber 18 in communication with said intake connection 11, and normally closed by suitable flat valve 19 which is maintained in its seated position by a spring 20 surrounding the stem 21 thereof, which stem may be guided in the

spider 22 formed in the central intake passage 23. To facilitate the lifting of the valve 19 under suction caused by the operation of the engine, it is also proposed to 5 provide a plurality of relatively small obliquely disposed air intake orifices 24 in the base 17 at the point where the said flange joins with the outer wall of the annular chamber 18.

10 Since the heated kerosene vapor is conveyed directly from the pipe 5 to the inlet connection 11 of the air mixer and thence into the annular chamber 18, it will be apparent that until the valve 19 is lifted, no 15 air is mixed with the vapor. However, as soon as the valve 19 is caused to lift, air will be drawn in through the passage 23 and over the vapor distributed in the chamber 18, and thence around the edges of the valve 19 against the inclined side of the casing 12, and, at the same time air will be drawn in through the inclined openings 24 in such 25 a manner that jets of air will penetrate the volume of air and gas passing up into the Venturi casing to thoroughly agitate the same and cause the proper mixing of gas and air. That is to say, owing to the oblique disposition of the openings 24 and their arrangement in circular formation 30 around the upper edge of the chamber 18, the air drawn therethrough by the operation of the engine will be injected into the volume of gas and air passing beneath the under surface of the valve head 19 in such 35 a manner that the various jets will converge and form a cone of air which will thoroughly mix the gas and air before being taken into the intake manifold of the engine.

40 In view of the foregoing, it will be apparent that the present invention proposes to provide a charge forming device which, because of the fact that it depends upon the heat of the exhaust gases to vaporize 45 the kerosene, is only operative after the engine is running. However, the initial starting of the engine may be conveniently accomplished by either placing a priming charge of gasolene in the cylinders or supplying the vaporizer unit itself with an initial supply of volatile fuel oil which will 50 vaporize under the suction of the engine and form the proper initial fuel charge. After the engine is initially started the heat 55 of the exhaust will cause a thorough vapor-

ization of the kerosene in the total absence of air, thus insuring a proper vapor for mixing with the air at the special type of mixer provided. In this way the proper mixing of the kerosene vapor and air is insured before the mixture enters the manifold of the engine, and, furthermore a uniform fuel charge is readily maintained, and the presence of raw fuel in the intake manifold is entirely avoided.

I claim:

1. A fuel vaporizer for internal combustion engines adapted to be interposed in the line of exhaust from the engine, said vaporizer being of tubular cross section and having an interior cross-shaped exhaust passage formed longitudinally therein and also a plurality of separate compartments each in communication with the other, means for supplying liquid fuel to one of said compartments, and means for conveying vaporized fuel therefrom.

2. A fuel vaporizer for internal combustion engines adapted to be interposed in the line of exhaust from the engine and including a tubular body portion having a threaded nipple extension at each end for fitting to the exhaust pipe, and also having an interior cross shaped exhaust passage extending longitudinally therethrough and forming within the tubular body a plurality of sector-shaped compartments, ports disposed transversely of the winged portions of the exhaust passage and arranged in such manner that fuel must travel the full length of each compartment and out at the opposite end from which it entered, means for supplying liquid fuel to the vaporizer, and means for conveying vaporized fuel therefrom.

3. A fuel vaporizer for internal combustion engines consisting of a vaporizing casting formed with means at each end for coupling with the exhaust pipe of the engine, and having an integral interior cross-shaped wall portion forming a passage-way for the heated exhaust gases through the vaporizer and dividing the interior of the latter into longitudinal vaporizing chambers.

In testimony whereof I hereunto affix my signature in the presence of two witnesses.

CLAUDE HARRISON COOK.
